UNITED STATES PATENT OFFICE.

THOMAS E. COPELIN, OF CHICAGO, ILLINOIS.

DESIGN FOR STICK-CANDY.

SPECIFICATION forming part of Design No. 15,851, dated February 24, 1885.

Application filed July 5, 1884. Term of patent 7 years.

To all whom it may concern:

Be it known that I, THOMAS E. COPELIN, a citizen of the United States, residing at Chicago, in the county of Cook and State of Illinois, have invented a new and original Design for Stick-Candy, of which the following is a specification, reference being had to the accompanying drawings, forming part thereof.

10 Figure 1 is a view in perspective, showing one edge and two sides of stick, and showing stripes to be of different colors, which are indicated by lines. Fig. 2 is a side view of stick, and lines represent the different color of stripes. Fig. 3 is an end view, and Fig. 4 is a cross-sectional view, of stick.

15

The leading feature of my design consists in the square shape of a stick of candy, combined with stripes of contrasting colors running from end to end and round the surface 20 of the stick.

What I claim as new, and desire to protect, is—

The design for a stick of candy having a square shape in cross-section, ornamented by 25 contrasting stripes, as shown and described.

THOMAS E. COPELIN.
